C. HARTER

BRAKE BEAM

Filed Nov. 21, 1921

UNITED STATES PATENT OFFICE.

CHARLES HARTER, OF ST. LOUIS, MISSOURI.

BRAKE BEAM.

Application filed November 21, 1921. Serial No. 516,629.

To all whom it may concern:

Be it known that I, CHARLES HARTER, a citizen of the United States of America, a resident of the city of St. Louis and State 5 of Missouri, have invented certain new and useful Improvements in Brake Beams, of which the following is a full, clear, and exact description, reference being had to the accompanying drawings, forming a part, 10 of this specification.

This invention relates to improvements in brake beams for railway rolling stock, and more particularly to a reversible brake beam adapted to receive either a live lever 15 or a dead lever. Prior to this invention, some types of brake beams have been provided with struts, known as fulcrums, and adapted to receive brake levers, while other 20 brake beams have been provided with fulcrums in the form of extended jaws adapted to receive brake levers. The ordinary brake lever fulcrum is permanently secured to the brake beam, and some fulcrums are arranged to receive live levers while others 25 are arranged to receive dead levers. The different levers usually lie at an angle of 40 degrees to a vertical line, but the brake beams of a car truck are oppositely disposed, so the ordinary brake beam having a 30 permanently secured fulcrum for one lever can not be reversed and substituted for a beam provided with a fulcrum for the other lever.

As a consequence, it is customary for railroad companies to carry a stock of brake beams having differently arranged brake lever fulcrums, and this usually involves a double investment for brake beams as well 35 as storage space for different beams, and the inconvenience of selecting the required beam whenever it is necessary to replace an old beam. I am aware that it is possible to remove some of the old types of brake lever fulcrums, and in this event a fulcrum 40 for a live lever could be rearranged to receive a dead lever. However, this is not in accordance with the ordinary practice, for the fulcrums are usually permanently secured to the beams.

Furthermore, in a trussed brake beam, the tension member is carefully adjusted 45 by a manufacturer having the facilities to accurately determine the adjustment, and the strut of the beam forms the brake lever

fulcrum, so if the fulcrum is removed or 55 loosened it would be necessary to relieve the tension in the beam.

One of the objects of the present invention is to produce a brake beam having a fulcrum adapted to receive either a live 60 lever or a dead lever. A further object is to provide means whereby either lever can be pivoted to the fulcrum without displacing the fulcrum. This is desirable on account of the difficulty of removing and replacing the fulcrum, and also for the reason that after a fulcrum has been displaced 65 it cannot be readily secured in another position, this being especially true in a trussed beam where the fulcrum is formed by a rigid strut between a compression member and a tension member.

To illustrate the invention, I have shown and will hereafter describe a brake beam having a compression member, a tension 75 member, and a brake lever fulcrum in the form of a strut between said members. The strut or fulcrum may be permanently secured between the compression and tension members, for it is not necessary to remove or 80 displace the strut. The strut, or fulcrum, is slotted or otherwise formed to provide guides for a dead lever and a live lever, and either lever can be pivotally secured to the beam without displacing the strut. The 85 guides for the different levers lie at an angle to each other, and the pivot can be adjusted to receive either lever. So far as I am aware, I am the first to produce a brake beam having a fulcrum of any kind adapted 90 to receive either an inclined live lever or an inclined dead lever without displacing the fulcrum relative to the body of the beam.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims hereunto appended.

Fig. I is a top view of a brake beam having a fulcrum embodying the features of this invention.

Fig. II is an enlarged transverse section taken approximately on the line II-II in Fig. I.

Fig. III is an enlarged transverse section taken approximately on the line III-III in Fig. I.

Fig. IV is a view similar to Fig. III showing the elements as they appear when a dead lever is mounted in the fulcrum.

Fig. V is a fragmentary side elevation looking in the direction indicated by the arrow V in Fig. III.

Fig. VI is a section showing the middle portion of the strut, or fulcrum, with the lever and its pivotal mounting omitted.

Fig. VII is a perspective view of one of the pivot-receiving blocks.

Fig. I shows a brake beam having a compression member 1, a tension member 2 and 20 brake heads 3 at the adjacent ends of said members. 4 designates nuts mounted on the ends of the tension member and adapted to engage the brake heads. These elements 1, 2, 3 and 4 may be made in any suitable 25 manner, and if desired the tension member can be permanently secured to the compression member.

A designates a hollow strut engaging and 30 rigidly held between the compression member 1 and tension member 2. This strut may be made of a single piece of metal, and it can be permanently secured to the members 1 and 2. It is adapted to receive brake levers, and struts of this general type are 35 known in the art as "brake lever fulcrums."

The hollow strut herein shown is provided with oppositely disposed longitudinal slots 5 adapted to receive a live lever L, shown in Figs. I, II and III. The strut is 40 also provided with oppositely disposed longitudinal slots 6 adapted to receive a dead lever D, shown in Fig. IV. The side walls of the slots for the live lever L are parallel with each other but at an angle to the side 45 walls of the slots for the dead lever D. As suggested by Figs. III and IV, the live lever L extends upwardly at one side of the strut A, and this upwardly extending portion preferably lies at an angle of 40 degrees 50 to a vertical line. As shown by Fig. IV, the dead lever D is inclined oppositely to the live lever, and the upwardly extending portion of the dead lever lies at an angle of 55 40 degrees to a vertical line. The side walls of the slots 6 for the dead lever D are therefore preferably formed at an angle of approximately 80 degrees to the side walls of the slots 5 for the live lever.

I will now point out the pivotal mounting 60 whereby either lever can be properly pivoted to the strut. B designates pivot-receiving blocks removably mounted in the hollow strut A and adapted to lie opposite each other as shown by Figs. III and IV. Each 65 block B has an arcuate outer face conform-

ing to the cylindrical inner face of the hollow strut. Each block is also provided with an extension 7 in the form of a lug adapted to lie within any one of the slots 5 and 6. As shown most clearly by Figs. V and VII, 70 each lug 7 has straight side faces adapted to engage the side walls of the slot in which the lug is mounted. 8 designates a brake lever pivot extending through apertures in the blocks B and also through the lever between said blocks. When the parts are assembled as shown by Figs. II and III, the live lever L passes through the oppositely disposed slots 5, and the side walls of these slots serve as guides for the live lever. The 75 blocks B have flat inner faces which lie flush with the side walls of slots 5 and engage opposite sides of the live lever. The lugs 7 on the block B then lie in the slots 6, and the pivot pin 8 extends through these slots 80 85. In Figs. II and III the axis of the pivot 8 lies at a right angle to the lever L, so the pivot is not parallel with the side walls of slots 6. Owing to the peculiar inclinations of the side walls of slots 5 and 6, 90 and for the reason that it is desirable to extend the pivot through these slots, one of the side walls of each slot is recessed as shown at 9 to receive an end portion of the 95 pivot pin.

The blocks B are movable from one slot to another to receive either the live lever or the dead lever. Figs. I, II and III show the blocks positioned to receive the live lever L, and Fig. IV shows them positioned to receive the dead lever D. When in either of these positions, the blocks B are disposed opposite to each other so as to extend into two of the oppositely disposed slots 5 or 6, while the interposed lever passes through 100 the other slots.

As shown by Figs. V and VI, the hollow strut is provided with internal thrust-receiving shoulders 10 adapted to engage the ends of the blocks B. When the parts are 110 assembled, each block lies between and engages the thrust-receiving shoulders 10, while its lug 7 lies between and engages the opposite side walls of a slot 5 or 6. The blocks are thus securely interlocked with the strut, and they are closely confined between the lever and the strut. The pivot pin 8 may be provided with a removable cotter pin 11 at one end and a head at the opposite end. The hollow strut is preferably 120 provided with longitudinal reinforcing ribs 12 between the adjacent slots 5 and 6.

Owing to the peculiar inclinations of the slots 5 and 6, each slot is recessed at 9 to receive a portion of the pivot pin, as previously pointed out, and for the same reason the pivot-receiving aperture in each block B is open at one side of the lug 7, as shown in Fig. VII.

It will now be understood that the brake 125

beam herein disclosed is reversible. In other words, it can be used with either a live lever or a dead lever, and although these levers are oppositely inclined, either 5 lever can be properly mounted at an angle of 40 degrees to a vertical line. Furthermore, either lever can be readily applied to the brake beam without displacing the strut A which serves as the brake lever fulcrum.

10 It is not necessary to loosen the tension rod 2, nor to disturb any of the main elements of the trussed beam, so the strut can be permanently mounted in a fixed position relative to the compression member 1 and 15 tension member 2.

I claim:

1. A reversible brake beam having a stationary brake lever fulcrum provided with slots for the reception of a live lever and a 20 dead lever, the slot for the live lever being formed at an angle other than a right angle to the slot for the dead lever, and means whereby either lever can be pivotally mounted in said brake lever fulcrum, said means 25 including a pivot adjustable from one of said slots to the other, said pivot being extended through the lever at a right angle thereto.

2. A reversible brake beam having a stationary brake lever fulcrum provided with slots for the reception of a live lever and a dead lever, the slot for the live lever being formed at an angle other than a right angle to the slot for the dead lever, and means 35 whereby either lever can be pivotally mounted in said brake lever fulcrum, said means including a pair of independent pivot-receiving members interlocked with said fulcrum and adapted to extend across said 40 slots, each of said pivot-receiving members being adjustable from one slot to the other to provide for the reception of either of said levers.

3. A reversible brake beam comprising a 45 compression member, a tension member, a brake lever fulcrum including a strut engaging and rigidly held between said compression and tension members, said strut having oppositely disposed longitudinal 50 slots for the reception of a live lever, said strut also having oppositely disposed longitudinal slots for the reception of a dead lever, the side walls of the slots for one lever being parallel with each other but at an 55 angle other than a right angle to the side walls of the slots for the other lever, and a brake lever pivot mounted in said strut and adjustable from one position to another to form a pivot for either of said levers, 60 said pivot being arranged to extend at a right angle through either of said levers.

4. A reversible brake beam comprising a 65 compression member, a tension member, a brake lever fulcrum including a strut engaging and rigidly held between said

compression and tension members, said strut having oppositely disposed longitudinal slots for the reception of a live lever, said strut also having oppositely disposed longitudinal slots for the reception of a 70 dead lever, the side walls of the slots for one lever being parallel with each other and at an angle of approximately 80 degrees to the side walls of the slots for the other lever, independent pivot-receiving 75 members located within the strut, and a brake lever pivot extending through said pivot-receiving members, said pivot and pivot-receiving members being adjustable to form a pivotal mounting for either of 80 the levers and said pivot being arranged to pass through either of said levers at a right angle thereto.

5. A reversible brake beam comprising a compression member, a tension member, a 85 brake lever fulcrum including a strut engaging and rigidly held between said compression and tension members, said strut having oppositely disposed longitudinal slots for the reception of a live lever, said strut also having oppositely disposed longitudinal slots for the reception of a dead lever, the side walls of the slots for one 90 lever being parallel with each other but at an angle of approximately 80 degrees to the 95 side walls of the slots for the other lever, and a brake lever pivot adapted to extend through one of said slots and through the lever in the other slot at a right angle thereto to form a pivot for said lever. 100

6. A reversible brake beam comprising a compression member, a tension member, a brake lever fulcrum including a strut engaging and rigidly held between said compression and tension members, said 105 strut having oppositely disposed longitudinal slots for the reception of a live lever, said strut also having oppositely disposed longitudinal slots for the reception of a dead lever, the side walls of the slots for one 110 lever being parallel with each other but at an angle of approximately 80 degrees to the side walls of the slots for the other lever, and a brake lever pivot adapted to extend through one of said slots and through the lever in the other slot at a 115 right angle thereto to form a pivot for said lever, each of said slots having a recess in one of its side walls to receive an end portion of said pivot. 120

7. A reversible brake beam having a compression member, a tension member, a brake lever fulcrum including a hollow strut rigidly held between said compression and tension members, said strut having 125 oppositely disposed longitudinal slots for the reception of a live lever, said strut also having oppositely disposed longitudinal slots for the reception of a dead lever, the side walls of the slots for the live lever 130

being parallel with each other but at an angle other than a right angle to the side walls of the slots for the dead lever, pivot-receiving blocks located within the hollow 5 strut, said blocks being movable from one slot to another to receive either the live lever or the dead lever, and a brake lever pivot extending through said blocks and through the lever between said blocks at 10 a right angle thereto, each of said slots having a recess in one of its side walls to receive an end portion of said brake lever pivot.

8. A reversible brake beam having a 15 compression member, a tension member, a brake lever, fulcrum including a hollow strut made of a single piece of metal engaging and rigidly held between said compression and tension members, said strut 20 having oppositely disposed longitudinal slots for the reception of a live lever, said strut also having oppositely disposed longitudinal slots for the reception of a dead lever, the side walls of the slots for the live lever 25 being parallel with each other but at an angle other than a right angle to the side walls of the slots for the dead lever, pivot-receiving blocks located within the hollow strut and extending into two of said slots,

the inner faces of said blocks being flush 30 with the side walls of the other slots and said blocks being movable from one slot to another to receive either the live lever or the dead lever, said hollow strut having internal thrust-receiving shoulders adapted 35 to engage the ends of said blocks, and a brake lever pivot extending through said blocks and also through the slots into which the blocks extend, said pivot being extended through the lever supported between said 40 blocks at a right angle thereto, each of said slots having a recess in one of its side walls to receive an end portion of said brake lever pivot.

9. A reversible brake beam having a 45 brake lever fulcrum fixed thereto and provided with guides for the reception of a live lever and a dead lever, said guides being at an angle other than a right angle to each other, and means passing through 50 one of said guides and extending at a right angle through a lever arranged in the other guide whereby said lever is pivoted to the fulcrum without displacing said fulcrum.

In testimony that I claim the foregoing I hereunto affix my signature.

CHARLES HARTER.
